UNITED STATES PATENT OFFICE

ISIDORE UNKER AND HENRY S. ROSENTHAL, OF NEW YORK, N. Y.

GARMENT GUARD OR PROTECTOR

Application filed December 11, 1926. Serial No. 154,094.

This invention relates to a new and improved garment guard or protector, and one of the objects of the invention is to provide a device adapted to be mounted upon and used in conjunction with a garment hanger, such that the shoulder portions of the garment will be protected against dust and dirt, which would ordinarily be deposited upon the exposed upper portions of the garment.

Another object is to provide a device of the above character, adapted to be mounted upon a garment hanger of the usual construction, such that the garment may be removed from the hanger without removing the protector from the hanger.

Another object of the invention is to provide a device of the above character which can be manufactured at a very low cost, so constructed that it may be collapsed for shipping or storage purposes, but which may be readily opened out and placed in condition for use.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein we have illustrated preferred forms of embodiments of our invention,—

Figure 1 is a front elevational view of a garment mounted upon a hanger, showing our improved protecting device or guard mounted thereon;

Figure 2 is a top plan view of a slightly modified form of construction;

Figure 3 is a sectional view taken on the line 3—3 of Figure 1;

Figure 4 is a similar view taken on the line 4—4 of Figure 1.

Referring now to the drawings, wherein similar reference characters refer to similar parts throughout the several views,—the reference numeral 1 denotes a garment mounted in the usual way on a common form of garment hanger 2, the latter being

provided with the usual form of hook 3, by means of which the garment hanger is suspended. The presence of the garment 1 on the drawings is, of course, purely for illustrative purposes.

Our improved guard or protecting device as illustrated in the embodiments shown in Figures 1 to 4 of the drawings is formed of two strips of relatively stiff material, preferably paper, although other materials if desired, may be used in this relation. These strips of paper which may be blanked from a suitable sheet of stock, are folded lengthwise of themselves, so as to form wings 4 and 5. The inner end portions of each of the wings 4 and 5 are cut away at the points 6 and 7, and each wing at the inner end portions is provided with a pair of ears 8—9 and 10—11. The ear 8 of the wing 4 is pivotally attached at 12 to the corresponding wing 10 of the wing 5, and the ear 9 of the wing 5 is similarly attached to the ear 11 of the wing 4 at the point 13. The pivots 12 and 13 which are preferably metallic rivets of the eyelet type, preferably interpose a slight frictional resistance to the relative swinging movement of the ears 4 and 5, so that said wings will preferably remain in such relative position as they may be moved. If desired, small circular friction washers 14 and 15 may be associated with the rivets 12 and 13, so as to better provide for this slight frictional resistance. The cut-away portions 6 and 7 of the wings provide the abutting shoulders 16 and 17 which will limit the relative upward swinging movement of the wings 4 and 5.

The wings 4 and 5, it will be seen, are of U or V-shaped cross section, whereby when the device is positioned upon the hanger, the said wings will rest upon the shoulder portions of the garment, thereby operating to catch dust and dirt present in the atmosphere, and prevent the same from being deposited upon the covered portions of the garment. The cut-away portions 6 and 7 of the wings adjacent their points of connection, form an opening through which the stem of the hook 3 extends.

Referring to Figures 1 and 4, it will be

seen that the wings 4 and 5 may be swung upwardly, whereby the garment may be readily removed from the hanger without the necessity of removing the protecting device therefrom.

5 The relation of the pivotal points of connection between the wings of the device, is such that when the device is in use it may be removed from the hanger and the wings 10 swung inwardly, so that one will be received within the other, whereby the device in this collapsed condition may be more readily shipped or packed.

In the embodiment of our invention 15 shown in Figure 2, the wings 4 and 5 are connected at the points 18 and 19 by an elastic band 20 which, by reason of its location in relation to the pivots 12 and 13 to the wings, will hold the latter at either side 20 of a dead center, so that the wings will be held in an upwardly moved or downwardly moved position by the elastic member 20.

It will accordingly be seen that we have 25 provided a construction well adapted to attain, among others, all the ends and objects of the invention in a very simple manner, and have provided a device possessed of great utility. The device may be usefully employed in establishments where a large 30 number of garments are on display, wherein it is desired to protect them from deposits of dust and dirt, thereby eliminating the item of labor required by the more or less constant necessity of dusting the garments.

The device also protects the garment 35 against fading which might be caused by its exposure to sunlight. Moreover, it will be seen that the exposed portions of the device may be utilized for advertising purposes, that is to say, the name of the maker of the garment may be displayed upon either the front or rear flaps of the wings.

As many changes could be made in this 45 construction without departing from the scope of the following claims, it is intended that all matter contained in the above description or shown in the accompanying drawings, shall be interpreted as illustrative only and not in a limiting sense.

Having thus described our invention, what we claim as new and desire to secure by Letters Patent, is:

1. In a device of the class described, the 55 combination with a garment hanger, having a supporting hook or member, of a dust guard or protector consisting of a pair of wings, the inner ends of which are pivotally connected, so that said wings may be swung 60 relatively to each other, friction devices co-operating with said pivotal ends whereby said wings may retain adjusted positions with respect to each other, and said wings being provided with side flaps, adapted to 65 engage with the shoulder portions of the

garment mounted upon said hanger, and having an opening through which the supporting hook or member of the hanger may extend.

2. A device of the class described, in combination with a garment hanger, a protector comprising two strips of relatively thin, stiff material, such as paper, bent longitudinally into V-shaped form, each strip being provided with ears, the ears of each strip being pivotally attached to the corresponding ears of the other strip, whereby the strips may be moved relatively to each other, friction devices cooperating with said ears whereby said wings may retain adjusted positions with respect to each other, the strips adjacent their point of connection being provided with an opening adapted to receive the supporting device of said garment hanger.

3. A device of the class described, in combination with a garment hanger, a protector comprising a strip of material divided into two sections, each of which is adapted to be bent longitudinally of its length into a V-shape to provide flaps, the adjacent flaps of both sections being provided with mutually engaging interlocking parts, whereby the said sections may be swung upwardly and held in a pre-determined position, the strip intermediate said sections being provided with an opening adapted to receive the suspending device of a garment hanger.

In testimony whereof, we affix hereto our signatures:

ISIDORE UNKER.
HENRY S. ROSENTHAL.
